REFRIGERATOR

Everett E. Fowler, New York, N. Y.

Application March 22, 1933, Serial No. 662,147

29 Claims. (Cl. 62—46)

This invention relates to refrigerators and it is more especially an improvement upon the structure disclosed in an application filed by George Lange, Rudolph Sommers and Mackay C. Saylor on October 25, 1932, Serial Number 639,488.

It is characteristic of this refrigerator that a corrugated partition or grid is interposed between the ice compartment and the storage or food compartment, this grid or partition being adapted to be chilled by ice and ice-water supported thereon so that the air circulating within the storage or food compartment does not come into direct contact with any part of the ice but will flow along the said chilled surface and will be maintained in a washed condition and in a desirable state of humidity by ice-water overflowing from the partition or grid.

An object of the present invention is to provide a means for preventing the escape of any portion of the air from the compartment being chilled into the compartment containing the ice.

It is another object of the invention to provide the refrigerator with a double grid whereby the circulating air is caused to travel with increasing velocity within restricted passages within the grid, the increasing velocity being in proportion to the drop in temperature of the air within the passages so that a substantially uniform meltage of the supported ice will be maintained throughout the area of the bottom surface thereof.

A still further object is to utilize excess ice-water for the purpose not only of washing and humidifying the air within the compartment being chilled but also to employ it as a water seal whereby the air can be guided properly to insure correct distribution thereof to different parts of the grid.

A still further object is to provide a means for keeping the air out of contact with the walls of the refrigerator at points where it leaves the cooling grid, thereby to prevent the walls from sweating at these points.

Another object is to so direct the flow of excess water as to insure thorough washing of the air and the maintenance of a substantially uniform percentage of humidity under all working conditions.

It has been found in practice that unless the flow of air is properly controlled along the surface of the ice supporting grid, the meltage of the ice at the point of first contact by the air with the grid will be much more rapid than at other points. Consequently the ice will not melt uniformly along its bottom surface and the effi-

ciency of the refrigerator will be reduced materially. The present invention has for an object to gradually speed up the velocity of the air as it moves away from its point of first contact with the grid so that while its temperature gradually lowers, the velocity of the air will increase to such an extent as to maintain a substantially uniform heat transfer, thereby insuring the uniform meltage which is so desirable.

With the foregoing and other objects in view which will appear as the description proceeds the invention resides in certain novel steps in the method of chilling air and in certain novel details of construction and combinations of parts which will be hereinafter more fully described and pointed out in the claims, it being understood that changes may be made in the construction and arrangement of parts and in the steps of the method herein disclosed without departing from the spirit of the invention as claimed.

In the accompanying drawings there has been illustrated a refrigerator constructed in accordance with the present invention, it being understood that the term "refrigerator" as herein used is to be construed as of sufficient scope to apply to any structure wherein one or more compartments are to be chilled by air circulating therein and chilled by an ice-cooled surface. Among such structures may be mentioned ordinary refrigerators of all sizes, show-cases or counters, rooms or compartments in buildings, railway cars, etc.

In said drawings:

Figure 1 is a vertical longitudinal section through the upper portion of a refrigerator, said section being taken longitudinally of the grid.

Figure 2 is a horizontal section through the ice compartment of the structure shown in Figure 1, a portion of the grid being broken away to show the pan and the air-distributing flue thereunder, a portion of the pan being broken away to show its supporting means.

Figure 3 is a vertical transverse section through the central portion of the grid at one side of the grid thereof, said section being on the line 3—3, Figure 1.

Figure 4 is a section through a portion of the grid taken on the line 4—4, Figure 3.

Figure 5 is a section on line 5—5, Figure 4.

Figure 6 is a section on line 6—6, Figure 4.

Figure 7 is an enlarged vertical transverse section through a portion of the grid and illustrating, more especially, the tapered passage for the flow of air between the members of the grid.

Referring to the figures by characters of ref- 55

erence 1 designates the casing of the refrigerator which can be of any suitable construction properly insulated. The interior of the casing is provided with a suitably located partition 2 which, 5 in large structures, can be mounted on supports 3. This partition separates the interior of the refrigerator into an ice compartment 4 and a lower or storage chamber 5. The partition 2 supports a pan 6 which is spaced from two opposed walls of 10 the structure 1 to provide air outlet spaces 7 opening downwardly into the compartment 5. The ends of the pan can extend up to the adjacent walls of the structure 1 so as to prevent communication between the compartments along said 15 ends.

An air-inlet opening 8 is formed within the pan preferably mid-way between the spaces 7 and extends practically from one end to the other of the pan. This opening coincides with an outer 20 trough 9 secured within an opening 10 in partition 2 and if desired the bottom of the trough can be formed with side flanges 11 detachably secured by bolts 12 or the like to the partition. An inner trough 13 is surrounded by the trough 9 and has 25 its walls spaced therefrom to form a continuous gutter 14. The bottom of this inner trough is provided with a drain outlet 15 adapted to discharge waste water into a drain pipe or the like. At any other suitable point in the trough there is 30 provided an air-inlet 16 for receiving air from the upper portion of the compartment 5. A blower or the like, not shown, can be utilized for setting up a forced circulation of air through this inlet 16.

The pan 6, which is provided at its edges with 35 a low wall or flange 17 is inclined downwardly gradually from said walled edges to the sides of the opening 8 and the trough 9 so that any water entering the pan will flow therealong and into the trough.

40 The grid which is used in connection with the pan consists of an upper plate 18 and a lower plate 19. The upper plate is formed with longitudinal corrugations having rounded crown portions or peaks 20, and cooperating to provide gutters 21. The ends of these gutters are closed by 45 end plates 22 so that water produced by the melting of ice supported on the corrugated plate 18 will be trapped in the gutters and chill the bottom and side faces thereof. One wall of each corrugation has an outlet-opening 23 at a predetermined 50 water level and extending to each of these openings is an overflow tube 24 or the like, the inlet end of which is below the level of the opening 23. Thus when the gutters 21 contain ice-water, the level of the water will be permitted to 55 rise until it reaches the openings 23 whereupon excess water will flow through the openings into the space under the corrugated plate 18. As the tubes 24 extend below the water level, it will not be possible for air which is under plate 18 to flow 60 through the openings 23 and come into contact with ice supported by the plate 18.

The plate 19 which is supported beneath the plate 18, has corrugations 25 which are straddled 65 by the corrugations of the plate 18 but are spaced therefrom. These corrugations 25 form dead air spaces 26 thereunder, the outer ends of which are closed by plates 27 while the inner ends of the dead air spaces are closed by a plate 28 which 70 extends downwardly into the gutter 14 and around the trough 13. Each of the corrugations 25 is gradually increased in size from its center toward its outer end so that the passages 29 provided between the corrugated plates 18 and 19

will gradually diminish in transverse area toward the ends of the corrugations.

Adjacent to the bottom of each of the corrugations 25 and between the spaces 26 there are provided air ports 30 which can be in the form of slots whereby air is free to flow into the passages 29.

A deflecting shield 31 is arranged in each of the outlet spaces 7 and is preferably formed of a sheet of metal the greater portion of which is out 10 of contact with the casing 1. These shields are arranged below abutments 32 which overlie the opposed sides of the grid plate 18 so as to cut off communication at these points between the compartments 4 and 5. The shields are curved outwardly and downwardly from the grid and serve 15 to deflect the air currents downwardly toward each other beneath the partition 2. At the same time, by using shields as described, the casing 1 will be prevented from sweating where the cold 20 air issues from between the grid plates.

In using this refrigerator the ice is stored in the chamber 4 so as to rest upon the upper plate 18 of the grid. The ice, through its contact with this plate will slowly melt at its bottom surface 25 and the ice-water thus produced will rise within the gutters 21 where the level of the water will be maintained by the openings 23. Portions of the ice will project into these gutters and remain 30 constantly in contact with the water trapped in the gutters with the result that the temperature of this water will be maintained at a low degree and a corresponding low temperature of the plate 18 will also be maintained.

Excess water will drain from the several gutters 21 through openings 23 into the passages 29 and will gravitate within these passages until it reaches the ends thereof whereupon it will flow onto the pan 6 at points back of the flanges or walls 17. The water, in a thin film, will then 40 flow along pan 6 toward the opening 8 where it will enter the outer trough 9 and fill the gutter 14. This will result in submerging the lower end of the plate 28 which not only closes the inner 45 ends of the dead air spaces 26 but also extends around the ends of the inner trough 13. This results in the formation of a water seal, as will be apparent by referring to Figure 3 and as the supply of water in the gutter is continued from pan 6 the excess will drain over the walls of the inner 50 trough 13 and flow to the outlet 15.

During the travel of the water as explained air is admitted through the inlet 16 and is distributed by inner trough 13 throughout the area surrounded by the water seal. The air will escape 55 by way of slots or ports 30 into the several passages 29. As the air cannot pass through the upper plate 18 by way of the openings 23 all portions thereof will be caused to flow longitudinally of the passages 29 toward the respective ends 60 thereof where it will escape over the adjacent ends of the pan 6 and be deflected downwardly by the plates 31 into the compartment 5.

The air is warmest at the point where it enters 65 the trough 13. Here it will be partly humidified and washed by the water to which it is exposed. As the air enters the ports 30 and travels along the 70 passages 29 it will be subjected to further humidifying and washing action through its contact with the water draining along said passages. Due to the gradual reduction in area of the 75 passages 29 toward their ends, resulting from the convergence of the corrugations of the two plates 18 and 19, the flow of the air toward the outlet ends of the passages can be so accelerated as to

effect a substantially uniform transfer of thermal units throughout the area of the plate 18 with the result that all portions of the bottom surface of the ice will be subjected to a substantially uniform melting action.

Importance is attached to the fact that it is impossible for any of the air within the compartment 5 to enter compartment 4, this being due to the fact that each of the water outlets 23 is 10 water-sealed by the tube 24.

Obviously as the air travels along the passages 29 it will sweep over the bottom surfaces of the corrugations of the upper plate 18 with gradually increasing pressure thereagainst so that its 15 temperature will be quickly lowered. As the air is also washed and humidified as heretofore explained, it becomes possible to keep it odorless; maintain in compartment 5 a low temperature which remains practically constant; and also 20 produce a high degree of humidity which remains substantially unchanged.

What is claimed is:

1. A refrigerator including an ice supporting grid comprising superposed plates having nested 25 corrugations contacting along their bottoms to provide air passages therebetween closed at their sides.

2. A refrigerator including an ice supporting grid comprising superposed plates having nested 30 corrugations contacting along their bottoms to provide air passages therebetween closed at their sides each having an air inlet and an air outlet, said passages being gradually reduced in size in 35 the direction of their outlets thereby to accelerate the velocity of the air in proportion to the drop in temperature of the air thereby to effect a uniform interchange of heat throughout the area of the grid.

3. A refrigerator including an ice supporting 40 grid comprising superposed plates having nested corrugations contacting along their bottoms to provide air passages therebetween closed at their sides each having an air inlet and an air outlet, said passages being substantially inverted 45 V-shaped in cross section and gradually reduced in size toward their outlets thereby to accelerate the velocity of the air in proportion to the drop in temperature of the air thereby to effect a uniform interchange of heat throughout the area of the grid.

4. A refrigerator including an ice supporting 50 grid comprising superposed plates having nested corrugations contacting along their bottoms to provide air passages therebetween closed at their sides, the corrugations of the lower plate converging toward one end of the corrugations in the upper plate to reduce the sizes of the passages gradually toward said end thereby to accelerate the velocity of the air in proportion to the drop 55 in temperature of the air thereby to effect a uniform interchange of heat throughout the area of the grid.

5. A refrigerator including an ice supporting 60 grid comprising superposed plates having nested corrugations providing air passages therebetween, the corrugations of the upper plate providing gutters for holding ice-water, and means adapted to be sealed by water in the gutters for directing excess water from the gutters into the air 65 passages.

6. A refrigerator including an ice supporting 70 grid comprising superposed plates having nested corrugations providing air passages therebetween, the corrugations of the upper plate providing 75 gutters for holding ice-water and the corrugations

of the lower plate providing dead air spaces thereunder, and means for distributing air into the corrugations under the lower plate at points outside of the dead air spaces, there being ports in said corrugations of the lower plate constituting inlets to the passages for the distributed air.

7. A refrigerator including an ice supporting grid comprising superposed plates having nested corrugations providing air passages therebetween, the corrugations of the upper plate providing gutters for holding ice-water, means adapted to be sealed by water in the gutters for directing excess water from the gutters into the air passages, and a pan extending under the grid for receiving water from the passages.

8. A refrigerator including a pan, an ice supporting grid on the pan comprising superposed plates having nested corrugations providing air passages therebetween, the corrugations of the lower plate forming dead air spaces thereunder, air distributing means opening through the pan for directing air under the grid but outside of the dead air spaces, there being ports for conducting the air through the lower plate into the passages between the plates, the corrugations of the upper 20 plate forming gutters for holding ice-water, and means adapted to be sealed by ice-water in said gutters for directing excess water from the gutters into the air passages, said air passages constituting means for guiding the water therein to the 25 outlet ends of the passages and delivering it onto the pan.

9. In a refrigerator including separate compartments, a pan having an air space across an edge thereof, an ice supporting grid supported by the pan and closing communication between the compartments, said grid including superposed plates having nested corrugations cooperating to form air passages therebetween opening above the pan into said air space, said passages being 40 gradually restricted toward said openings, there being air inlets in the lower plate opening into the 45 passages.

10. In a refrigerator including separate compartments, a pan having an air space across an edge thereof, an ice supporting grid supported by the pan and closing communication between the compartments, said grid including superposed plates having nested corrugations cooperating to form air passages therebetween opening above 50 the pan into said air space, said passages being gradually restricted toward said openings, there being air inlets in the lower plate opening into the 55 passages, the corrugations of the upper plate providing gutters for ice-water, and means adapted to be sealed by water within the gutters for delivering excess water from the gutters into the air passages.

11. In a refrigerator including separate compartments, a pan having an air space across an 60 edge thereof, an ice supporting grid supported by the pan and closing communication between the compartments, said grid including superposed plates having nested corrugations cooperating to form air passages therebetween opening 65 above the pan into said air space, said passages being gradually restricted toward said openings, there being air inlets in the lower plate opening into the 70 passages, the corrugations of the upper plate providing gutters for ice-water, means adapted to be sealed by water within the gutters for delivering excess water from the gutters into the air passages adjacent to the air inlets for delivery along said passages to the pan.

12. In a refrigerator including separate com- 75

partments, a pan having an air space across an edge thereof, an ice supporting grid supported by the pan and closing communication between the compartments, said grid including superposed plates having nested corrugations cooperating to form air passages therebetween opening above the pan into said air space, said passages being gradually restricted toward said openings, there being air inlets in the lower plate opening 10 into the passages, the corrugations of the upper plate providing gutters for ice-water, means adapted to be sealed by water within the gutters for delivering excess water from the gutters into the air passages adjacent to the air inlets for delivery 15 along said passages to the pan, and a deflecting shield suspended in the air space at the edge of the pan for directing air downwardly across said edge and under the pan.

13. In a refrigerator including separate compartments, a pan having an air space thereacross, an ice supporting grid supported by the pan and closing communication between the compartments, said grid including superposed plates having nested corrugations cooperating to 20 form air passages therebetween opening above the pan into said air space, said passages being gradually restricted toward said openings, there being air inlets in the lower plate opening into the passages, the corrugations of the upper plate 25 providing gutters for ice-water, means adapted to be sealed by water within the gutters for delivering excess water from the gutters into the air passages adjacent to the air inlets for delivery along said passages to the pan, an air distributing 30 trough opening through the pan and into the air inlets, means cooperating with the lower corrugated plate for providing dead air spaces thereunder, and means cooperating with the trough for receiving water from the pan to provide 35 a water seal between the trough and the dead air spaces.

14. A refrigerator including separate chambers, a grid for supporting ice in one of the chambers, said grid having air passages therein 40 for the circulation of air to and from the second chamber, and airtight means for delivering excess ice-water from the ice holding chamber into the passages.

15. A refrigerator including separate chambers, a grid for supporting ice in one of the chambers, said grid having air passages therein for the circulation of air to and from the second chamber, airtight means for delivering excess ice-water from the ice holding chamber into the 45 passages, and means sealed by water delivered from the passages for directing air into the passages from said second chamber.

16. A refrigerator including separate chambers, a grid constituting the bottom of one of the chambers, said grid constituting means for supporting ice and ice-water in said chamber, 50 passages in the grid for circulating air to and from the other chamber, said passages having means for gradually accelerating the flow of air 55 while traveling therein, and air-tight means for delivering excess ice-water from the ice holding chamber into the passages and the air currents therein.

17. A refrigerator including an ice chamber, 60 gutters in the bottom of the ice chamber for receiving and retaining water produced by the meltage of ice in said chamber, and water sealed means for maintaining the water at a predetermined depth in the gutters.

75. 18. A refrigerator including an ice chamber,

non-communicating ice-supporting gutters in the bottom of the ice chamber for receiving and retaining water produced by the meltage of ice in said chamber, and water sealed means for maintaining the water at a predetermined depth in the gutters. 5

19. A refrigerator including an ice chamber, non-communicating ice-supporting gutters in the bottom of the ice chamber for receiving and retaining water produced by the meltage of ice in 10 said chamber, a second chamber, means for guiding the air of said second chamber along the bottom faces of the gutters to cool the air, and water sealed means for maintaining the water in said gutters at a predetermined depth 15 and delivering excess water from the gutters into the air being cooled.

20. A refrigerator including separate compartments, a horizontal ice supporting grid constituting the bottom of one of the compartments, 20 there being an outlet for delivering ice-water from one compartment to the other and for maintaining the water at a uniform depth on the grid, and means for effecting a waterseal at the outlet for the exclusion of air therefrom. 25

21. A refrigerator including separate compartments, a substantially horizontal grid constituting the bottom of one of the compartments for holding both ice and ice-water in said compartment, overflow means for maintaining the water 30 on the grid at a uniform depth, and means cooperating with the ice-water in the overflow means for preventing the flow of air to the ice containing compartment from the other compartment. 35

22. A refrigerator including a pan, an ice supporting grid on the pan comprising superposed plates having nested corrugations providing air passages therebetween, the corrugations of the lower plate forming dead air spaces thereunder, 40 air distributing means opening through the pan for directing air under the grid but outside of the dead air spaces, there being ports for conducting the air through the lower plate into the passages between the plates, the corrugations of the 45 upper plate forming gutters for holding ice-water, and means for directing excess water from the gutters into the air passages, said air passages constituting means for guiding the water therein to the outlets of the passages and delivering 50 it onto the pan.

23. In a refrigerator including separate compartments, a pan having an air space across an edge thereof, an ice supporting grid supported by the pan and closing communication between the compartments, said grid including superposed plates having nested corrugations cooperating to form air passages therebetween opening above the pan into said air space, said passages being gradually restricted toward said openings, 60 there being air inlets in the lower plate opening into the passages, the corrugations of the upper plate providing gutters for ice water, and means for delivering excess water from the gutters into the air passages. 65

24. In a refrigerator including separate compartments, a pan having an air space across an edge thereof, an ice supporting grid supported by the pan and closing communication between the compartments, said grid including superposed plates having nested corrugations cooperating to form air passages therebetween opening above the pan into said air space, said passages being gradually restricted toward said openings, 70 there being air inlets in the lower plate opening 75

into the passages, the corrugations of the upper plate providing gutters for ice-water, and means for delivering excess water from the gutters into the air passages adjacent to the air inlets for delivery along said passages to the pan.

25. A refrigerator including an ice supporting grid comprising superposed plates having nested corrugations providing air passages therebetween, the corrugations of the upper plate providing gutters for holding ice-water, and means for directing excess water from the gutters into the air passages.

26. A refrigerator including a pan, an ice supporting grid on the pan comprising superposed plates having nested corrugations providing air passages therebetween, the corrugations of the lower plate forming dead air spaces thereunder, air distributing means opening through the pan for directing air under the grid but outside of the dead air spaces, there being ports for conducting the air through the lower plate into the passages between the plates, the corrugations of the upper plate forming gutters for holding ice-water, and means for directing excess water from the gutters into the air passages, said air passages constituting means for guiding the water therein to the outlets of the passages and delivering it onto the pan.

27. In a refrigerator including separate compartments, a pan having an air space across an edge thercof, an ice supporting grid supported by the pan and closing communication between the compartments, said grid including superposed plates having nested corrugations cooperating to form air passages therebetween opening above the pan into said air space, said passages being gradually restricted toward said openings, there being air inlets in the lower plate opening into the passages, the corrugations of

the upper plate providing gutters for ice water, and means for delivering excess water from the gutters into the air passages.

28. In a refrigerator including separate compartments, a pan having an air space across an edge thereof, an ice supporting grid supported by the pan and closing communication between the compartments, said grid including superposed plates having nested corrugations cooperating to form air passages therebetween opening above the pan into said air space, said passages being gradually restricted toward said openings, there being air inlets in the lower plate opening into the passages, the corrugations of the upper plate providing gutters for ice-water, means for delivering excess water from the gutters into the air passages adjacent to the air inlets for delivery along said passages to the pan.

29. A refrigerator including a pan, an ice supporting grid on the pan comprising superposed plates having nested corrugations providing air passages therebetween, the corrugations of the lower plate forming dead air spaces thereunder, air distributing means opening through the pan for directing air under the grid but outside of the dead air spaces, there being ports for conducting the air through the lower plate into the passages between the plates, the corrugations of the upper plate forming gutters for holding ice-water, means adapted to be sealed by ice-water in said gutters for directing excess water from the gutters into the air passages, said air passages constituting means for guiding the water therein to the outlet ends of the passages and delivering it onto the pan, and a structure extending around the air distributing means for receiving water from the pan to form a water seal for said air distributing means.

EVERETT E. FOWLER.
